FLEXIBLE SHAFT WELL DRILLING EQUIPMENT

John S. McCune and William E. Hanks, Long Beach, Calif., assignors to Oilwell Drain Hole Drilling Co., Long Beach, Calif., a corporation of California

Application March 31, 1952, Serial No. 279,556

7 Claims. (Cl. 255—1.6)

1

This invention relates to improvements in well drilling equipment of the type employed for the drilling of so-called drain holes, i. e. lateral bores usually having right-angle deviation from the normal relatively straight or vertical well bore, and which are drilled to penetrate the formation widely at any of various locations about the main bore to increase the total drainage or inflow of production oil from the formation. Particularly contemplated are improvements in such drilling equipment, employing a drill string having a bottom flexible section or drill collar carrying at its lower end a bit which by reason of the flexible connection of the drill collar may be deflected at unusually wide or sharp angles from the main bore, and thus enable the drain hole to be drilled at angles that may approach or go above a horizontal course in relation to the point of deflection or whipstocking.

The invention may be further characterized as dealing with such drain hole equipment employing the combination of a flexible drill collar and a tubular sheath serving various functions, among which are its use as a housing for the full length of the drill collar in the relative positions assumed by the parts before the drain hole drilling commences, also as a carrier for the whipstock, and further as a carrier for such means as may be used to vertically position the whipstock in its bit deflecting position within the well. As will appear, under normal operating conditions, the composite flexible drill collar and its enclosing sheath may be run into the well, oriented in set position for deflection of the drill bit in the proper direction, with the drill collar then being movable downwardly within the sheath to project the bit and progressively the drill collar, out through an opening in the side of the sheath. Thereafter upon completion of an initial drain hole so drilled, the drill collar and bit may be retracted into the sheath and the assembly reset and reoriented for the drilling of one or more additional drain holes in selected directions. After completion of the drilling, the drill collar and sheath assembly may be pulled from the well.

Conditions may arise where it becomes desirable to pull the pipe string and drill collar, leaving the entire sheath or at least the lower extent thereof in the well. Such desirability may arise, for example, in the event the sheath becomes lodged in the formation, or where it may be found advantageous to retain the sheath in a previously set or oriented position for reception of a rerun bit and drill collar at some

2

future time, or for passage of a liner into a drilled drain hole.

Accordingly, our major object is to provide for disconnecting of the drill string from the sheath, or from at least the greater lower extent of the sheath, by a type of releasable interconnection between the parts which will assure independent removal of the drill string as a result of simple manipulations. Specifically, the invention contemplates the setting structure including sections interconnected by a left-hand threaded joint, and which may be disconnected at the joint by interengaging shoulders or lugs on both the drill string and sheath, so formed as to assure positive interengagement between the parts, and therefore positive transmission of left-hand rotation of the drill string to the joint to be broken.

All the various features and objects of the invention will be fully understood from the following detailed description of an illustrative embodiment shown by the accompanying drawing, in which:

Fig. 1 is a general view, for the most part in elevation, showing the drill collar and sheath assembly set in operative position within the well;

Figs. 2a and 2b are vertically continuing views showing respectively the upper and lower portions of the drill collar and sheath assembly in section;

Fig. 3 is a cross-section on line 3—3 of Fig. 2a;

Figs. 4a and 4b are vertically continuing views illustrating a variational form of the invention; and

Fig. 5 is a section on line 5—5 of Fig. 4a.

The drill string run down within the well bore 10 is shown to comprise an upper course of standard drill pipe 11 running to the ground surface, and a flexible lower section or drill collar 12 connected to the drill pipe by sub 13, the latter having an upper box end receiving at 14 the threaded pin of the tool joint 15, the sub having at its lower end a pin 16 threaded into the tapered box of the upper drill collar section 17. At its lower end the drill collar 12 is connected by way of the knuckle joint generally indicated at 18, with an appropriate drill bit 19.

The details of a suitable form of flexible drill collar 12 are more particularly dealt with in our copending application Ser. No. 279,557, filed on even date herewith. For present purposes it will suffice to describe the drill collar as comprising a series of tubular sections 17 and 20 interlocked at their adjacent ends for relative swinging

movement by flexible joints 21 each comprising two series of lobes 22 formed on the end of each section and received within corresponding recesses 23 between the similar lobes on the other section, the lobes on each section being spaced at ninety degrees to present two pairs of diametrically opposed lobes, with the pairs at ninety degree angularity, so that the joint sections are relatively movable or swingable in two directions at the same location longitudinally of the drill collar. Each section may carry between the lobes suitable anti-friction means to minimize wearing interengagement with the later described sheath, such an anti-friction means comprising typically a rubber ring 24 retained within a recess 25 in the section.

Closed circulation of fluid from the drill string thence through the drill collar, knuckle joint 18 to the bit 19, occurs by way of a hose 26 contained within the drill collar bore 27 and suitably held in place as by a hose coupling-type fitting 28 securing the upper end of the hose within the bore of section 17, and a fitting 29 connecting the lower end of the hose with a float- 25 ing peripherally sealed insert 30 movable within bore 31.

The knuckle joint 18 is shown typically to comprise a tubular body 32 containing a curved seat 33 engageable by the spherical head 34 of the knuckle leg 35 which is capable of swinging movement in the transverse plane defined by the diametrically opposed slots 36 in the head 34 and which receive the guide pins 37. In the assembled condition of the knuckle joint, upward displacement of the head is limited by its engageability with peripherally sealed tubular insert 39, upward movement of which is limited by the pin shoulder 39. The leg 35 is connected at 40 to the bit shank 41 which may carry spiral flights 42 which serve the purpose of guiding and stabilizing the bit during drilling.

The sheath structure generally indicated at 43 comprises an elongated tubular body having upper and lower sections 44 and 45 interconnected by a left-hand threaded joint at 46, the sheath also including suitable means for positioning it vertically in operative location within the well, and for retaining the sheath in oriented position. Merely as illustrative of such means, the sheath is shown to carry at its lower end a leg 47 having a bottom anchor or shoe 48 which when set down on the bottom of the hole will retain the orientation of the sheath. The lower sheath section 45 contains a side opening 49 above an inclined solid whipstock face 50 the purpose of which, as will appear, being to deflect the bit and progressively the drill collar, out through the opening 48 along the drain hole course indicated at 51.

The sub 13 carries a plurality of circularly spaced ribs or lugs 52 which are positively engageable against shoulders on the upper sheath section 44, and formed for example as depending lugs 53 on a tubular insert 54 retained within the upper end of the sheath by shear pin 55 which extends at 56 into the sub 13 and forms a releasable connection between the drill string and the sheath.

In considering the operation of the equipment, assume the drill collar and sheath assembly to be lowered into the well in the condition shown in Fig. 1. Here the shear pin 55 connection between the parts positively but releasably retains the full length of the flexible drill collar within the sheath, and permits such rotational posi-

tioning of the assembly as may be desired for orientation of the whipstock face 50. Following such orientation the imposition of load on the drill string shears pin 55 between the sub and insert 54, permitting the bit 19 to be lowered against and deflected outwardly by the whipstock face 50. The drain hole 51 then is drilled by rotation and progressive advancement of the bit and drill collar out of the sheath into the formation. At completion of the drilling, the entire assembly may be removed from the well by raising the drill string from the Fig. 2a position in which lugs 52 may carry the sheath as the tools are pulled from the well.

In the event that following drilling it is desired to pull the drill string and leave the lower sheath section 45 in the well, the string may be raised to the Fig. 2a position of interengagement between lugs 52 and 53. Thereupon right-hand rotation of the drill string is positively transmitted through the lugs to the joint 46 which by reason of its left-hand thread formation, may be unscrewed to free the upper sheath section 44 for withdrawal with the drill string.

Figs. 4 and 5 illustrate a variational form of the invention generally similar to the described embodiment but differing primarily in that it embodies a form of connection between the drill string and the sheath whereby if desired the entire sheath may be left in the well following a drilling operation. As will appear, this same association between the drill string and sheath permits the removed flexible drill collar and bit to again be run into the sheath remaining in the well, depending upon the requirements of the particular operation being conducted.

Referring to Figs. 4a and 4b, the drill pipe 11, sub 13, flexible drill collar 12, knuckle joint 18 and bit 19 correspond to the previously described parts and are given the same reference numerals. Here the sheath 60 may comprise upper and lower sections 61 and 62 interconnected at 63 by left-hand threaded or other suitable form of breakable joint. As before, the upper section 61 may carry ring segments 64 each presenting a depending lug or stop shoulder 65 engageable by a pair of diametrically opposed lugs 66 on the sub 13. Shear pin 67 releasably interconnects the sheath and hub. Between the ring segments 64 is a pair of diametrically opposed grooves or ways 68 adapted to receive and pass the sub-carried lugs 66, as will presently appear. At this point it may be mentioned that the internal diameter of the sheath within the ring segments 64 is sufficiently greater than the external diameter of the drill collar 12 and bit 19 to permit elevation of the drill string up through and out of the sheath.

In considering the operation of the tool, assume the sheath 60 to be oriented to proper bit deflecting position, and that the drilling is being completed by lowering the drill string (after severance of the shear pin 67) and advancement of the bit and drill collar to the desired extent of penetration into the formation. If it is desired to leave the entire sheath and whipstock structure in the hole, the drill string is elevated and turned so that lugs 66 are brought into alignment with the grooves 68, whereupon the sub, drill collar and bit may be raised out of the sheath. Thereafter the bit and drill collar may be run back down into the sheath by lowering through the ring segments 64 with lug 66 and recesses 68 aligned to pass the lugs 66 into the sheath. If it is thereafter desired to leave the

lower sheath and whipstock section 62 in the well, the lugs 66 may be raised to the Fig. 4a position of engageability with lugs or shoulders 65 and the string then rotated to unscrew the joint at 63 and free the upper sheath section 61 for removal from the well with the drill string.

We claim:

1. The combination comprising a vertically elongated tubular sheath having an opening in its side and including means for deflecting a drill bit run down within the sheath outwardly through said opening, the sheath having upper and lower sections interconnected by a joint releasable by counter-clockwise rotation of the upper section, a drill string including a flexible tubular drill collar carrying a bit and extending downwardly into the sheath through its upper end, said drill collar being movable from an upper position in the sheath downwardly therein to deflect and advance the bit outwardly through said opening, and said upper section and the drill string having lugs interengageable in an upper position of the drill collar in the sheath to disconnect said upper section from the lower section by counter-clockwise rotation of the drill string.

2. The combination defined in claim 1, including also releasable means holding the drill collar against downward movement in the sheath from said position in which said lugs on said upper section and drill string are interengageable.

3. The combination defined in claim 1, including also a shear pin releasably interconnecting the drill string and sheath and holding the drill collar against downward movement in the sheath from said upper position in which said lugs on said upper section and drill string are interengageable.

4. The combination as defined in claim 1, in which said lugs of the upper sheath section are formed on a tubular insert within the top of the sheath.

5. The combination comprising a vertically

elongated tubular sheath having an opening in its side and including means for deflecting a drill bit run down within the sheath outwardly through said opening, the sheath having upper and lower sections interconnected by a joint releasable by counter-clockwise rotation of the upper section, a drill string including an upper standard pipe section and a reticulated flexible tubular drill collar carrying a bit and extending downwardly within the sheath, a sub interconnecting the drill pipe and drill collar and extending through the top of the sheath, said drill collar being movable from an upper position in the sheath downwardly therein to deflect and advance the bit through said opening, and said upper section and the sub having lugs interengageable in an upper position of the drill collar in the sheath to disconnect said upper section from the lower section by counter-clockwise rotation of the drill string.

6. The combination defined in claim 5, including also releasable means holding the drill collar against downward movement in the sheath from said position in which said lugs on said upper section and sub are interengageable.

7. The combination defined in claim 5, including also a tubular insert within said upper section and carrying the sleeve lugs, and a shear pin releasably interconnecting said upper section and the sub in said position in which said lugs on said upper section and sub are interengageable.

JOHN S. McCUNE.
